METHOD OF MANUFACTURING A CONNECTOR TUBULAR SPLICE WITH WORKED INNER SERRATIONS

Marvin Lee, Rye, and Irving Frederick Matthysse, Bronx, N. Y., assignors to Burndy Engineering Company, Inc., a corporation of New York

Application January 17, 1942, Serial No. 427,130

1 Claim. (Cl. 29—148)

This invention relates to connector splices for wires and more particularly to a method of manufacturing an electrical connector.

Hitherto it has been found desirable to introduce hard particles on the inner surface of the tubular sleeve, which "keyed" the conductor to the sleeve when the sleeve was compressed by some suitable tool on the conductor. These methods have always resulted in producing additional contact layers and particles of lower conductivity than the connector wall, thus increasing the resistance of the connection and lowering the electrical joint efficiency.

We have discovered that it is possible to cold work the inner metal surface of the tubular sleeve and produce hardened irregularities which will "key" into the conductor when the sleeve is compressed.

A primary purpose of our invention therefore is to compress a tubular sleeve on a mandrel having suitable serrations, which will cause a cold working of the inner surface of the tubular sleeve and harden it in the desired form.

Another object is to provide means whereby the mandrel may be removed after the sleeve has been worked thereon.

We accomplish these and other objects and obtain our new results as will be apparent from the device described in the following specification, particularly pointed out in the attached claim, and illustrated in the accompanying drawing, in which:

Fig. 1 is a longitudinal sectional view of a die compressing the connector sleeve to a mandrel.

Fig. 2 is a sectional view of the same taken along line 2—2 of Fig. 1 and in the direction indicated by the arrows.

Fig. 3 illustrates a method of removing a mandrel with longitudinal serrations.

Fig. 4 illustrates a method of removing a mandrel with threaded serrations.

Fig. 5 illustrates a cross-sectional view of a collapsible type of mandrel.

Fig. 6 illustrates a method of rolling a sleeve on a mandrel.

Fig. 7 and 8 illustrate a method of compressing two sides of a sleeve on a mandrel.

Fig. 9 illustrates a method of compressing the two remaining sides of the sleeve on the mandrel.

Fig. 10 illustrates a method of rounding out a compressed and distorted sleeve.

Figs. 11 and 12 illustrate a longitudinal sec-

tional view of a method of rolling a sleeve on a longitudinally rounded mandrel.

Fig. 13 is a transverse sectional view of the same.

Fig. 14 illustrates a top view of a sleeve compressed onto a pair of wires.

Fig. 15 is a longitudinal sectional view of the same.

Referring more particularly to the drawing, reference numeral 10 designates a tubular metal sleeve with a bore 11, and a mandrel 12 provided with longitudinal serrations 13 circumferentially arranged thereabout. The bore 11 is slightly larger than the mandrel which is inserted therein, and a pair of compressing dies 14 and 15 are applied to the external surface of the sleeve to cause the inner surface of the bore 11 to assume the serrated form of the mandrel 12. The sleeve and mandrel may be rotated in the dies, to give the entire inner surface of the sleeve the serrated form.

Since the serrations 13 of the mandrel 12 are longitudinal to its axis, the mandrel may be laterally withdrawn from the sleeve. This is accomplished by applying a cylindrical tool 16 to the mandrel 12, and forcing the sleeve 10 against a plate 17, having an aperture 18, through which the mandrel 12 is forcibly withdrawn. This leaves the tubular sleeve 10 with hardened longitudinal serrations intact.

The mandrel may be narrowed at one end, as at 13a, and forced through the tubular sleeve 10, the gradually increasing diameter, 13b, working the inner surface into the desired shape. This is possible with longitudinally extending serrations.

A method of applying spirally shaped serrations to the inside of a sleeve is shown in Fig. 4. This consists in applying a set of compressing dies (not shown) to a sleeve 20, about a threaded mandrel 21. When the mandrel is removed, as by rotating its head 22, the inner surface of the tubular sleeve 20, is provided with threaded serrations 23 which are formed into the worked inner surface of the tubular sleeve by the compressing action of the dies.

In Fig. 5, we have shown a sectional view of a collapsible type of mandrel inserted in a tubular sleeve 25. Here the mandrel is provided with a plurality of circumferential segments 26, and an inner cylindrical member 27 which may be withdrawn causing the outer segments to collapse and permit their withdrawal. The inner cylindrical member 27 may be provided with

tongues 28 interlocking with grooves 29 to hold the various segments in position.

In Fig. 6, we illustrate a sleeve 30, with mandrel 31 of lesser diameter than the inner bore 32 of the sleeve. The sleeve and mandrel are placed between rolling dies 33 and 34 which compress the sleeve 30 on the mandrel 31, and simultaneously move in opposite directions as indicated by the arrows, to insure that the entire inner surface of the sleeve is serrated. The rolling dies may be roughened at surfaces 35 and 36 to insure rolling the sleeve. When the action is completed, the slightly ovalized sleeve is placed in rounding dies 37 and 38 as shown in Fig. 10, which are provided with sockets 39 and 40 for shaping the sleeve in the full round condition to permit the mandrel to be removed from the sleeve.

An additional method of working the sleeve on the mandrel to produce the desired inner serrations, is shown in Figs. 7 to 9. Here the compressing dies 42 and 43 compress the sleeve 44 on the mandrel 45 so that inner serrations are caused on two opposite longitudinal regions of contact. This ovalizes the tubular sleeve, as shown in Fig. 8, which thereafter is rotated 90° and recompressed, causing an additional two regions of serrations. The sleeve and mandrel may be rotated to secure any number of impressions with corresponding serrations. Thereafter the sleeve and mandrel are placed in a rounding die as previously explained, and illustrated in Fig. 10, where the mandrel may be removed.

One more method of working serrations on the inner surface of a sleeve is shown in Figs. 11, 12, and 13. Here the mandrel 46 is inserted into the connector sleeve 47 and supported at each end 48 and 49. A roller 50 is rolled over the outer surface of the sleeve 47, causing the sleeve and mandrel to roll with it. The serrations are actually rolled into the inner surface as the roller 50 rotates. Since the mandrel is unsupported at the center thereof, it may be made slightly rounded longitudinally, so that the compressing force will flatten it out and substantially cover the entire inner surface. The flattened mandrel is shown in Fig. 12, and a sectional view of the arrangement is shown in Fig. 13.

The serrations, as we have explained, may be longitudinal or spiral to facilitate removal of the mandrel, or transversely formed. A mandrel which leaves individual projections of desirable height throughout the inner surface of the sleeve, either as flat cones, pyramids, or other forms, is suitable. The mandrel may also cause indentations in the inner sleeve without changing the sleeve diameter. This would not interfere with the entrance of the wires to be spliced, and possibly affect the cross-section of the wire least.

The mandrel should, of course, be made of metal considerably harder than the sleeve.

A compressing tool for causing indentations on the outer surface of the sleeve is used to "key" the sleeve to the wires. This type of indentation is shown in Figs. 14 and 15, and results in the finished splice. Tools for accomplishing the final indentations which may be of any sort, are well known in the prior art.

10 By use of interrupted indentations, as shown in Fig. 14 and Fig. 15, the longitudinally applied internal worked serrations may be compressed into the conductor, and act to resist the tensile forces applied to the conductor without reducing the net cross-section of the conductor.

15 By using our method of cold working the inner surface of the sleeve, we have obtained a method of splicing connectors to wires that reaches ultimate results both as to "pull out" values and as to the electrical joint efficiency. The "keys" are actually of the same metal as the sleeve and consequently possess the same conductivity.

20 The connector may be of the splice type for joining two wires, of the terminal or dead end type for joining a single wire to a plate or rod.

25 We have thus described our invention, but we desire it understood that it is not confined to the particular forms or uses shown and described, the same being merely illustrative, and that the 30 invention may be carried out in other ways without departing from the spirit of our invention, and, therefore, we claim broadly the right to employ all equivalent instrumentalities coming within the scope of the appended claim, and by 35 means of which, objects of our invention are attained and new results accomplished, as it is obvious that the particular embodiments herein shown and described are only some of the many that can be employed to attain these objects and 40 accomplish these results.

What we claim and desire to secure by Letters Patent is as follows:

45 The method of manufacturing an electrical connector for attachment to a conductor by indentation, which comprises the step of providing a seamless cylindrically shaped sleeve having smooth sides and made of malleable metal hardenable by swedging and suitable for transmitting a current therethrough, and work-hardening by 50 swedging the metal forming the inner surface with a series of irregularities projecting from the inside of the sleeve, from end to end and increasing the hardness of the metal to a degree sufficient to penetrate the conductor, to provide 55 work-hardened keying-in sections suitable for indentation into the conductor by compression.
